US0D1014556S

(12) **United States Design Patent** (10) Patent No.: **US D1,014,556 S**
 (45) Date of Patent: ** Feb. 13, 2024

(54) **DISPLAY SCREEN WITH ICON**

(71) Applicant: **NOVADELTA—COMÉRCIO E INDÚSTRIA DE CAFÉS, LDA,**
 Lisbon (PT)

(72) Inventors: **Rui Miguel Nabeiro**, Campo Major (PT); **Filipe Alexandre Correia**, Mafra (PT)

(73) Assignee: **NOVADELTA—COMÉRCIO E INDÚSTRIA DE CAFÉS, LDA,**
 Lisbon (PT)

(**) Term: **15 Years**

(21) Appl. No.: **29/883,832**

(22) Filed: **Feb. 3, 2023**

Related U.S. Application Data

(62) Division of application No. 35/512,448, filed on May 20, 2021 (U.S. filing date under 35 U.S.C. 384), and having an international filing date of May 20, 2021.

(57) CLAIM

We claim the ornamental design for display screen with icon, as shown and described.

DESCRIPTION

The FIGURE is a front view of a display screen with icon. The outermost broken line rectangle shows the display screen, and forms no part of the claimed design. All other broken lines show portions that form no part of the claimed design.

1 Claim, 1 Drawing Sheet

Capullo
 Container
